UNITED STATES PATENT OFFICE

GEORGE FORBES, OF WESTMINSTER, ENGLAND.

APPARATUS FOR SETTING THE SIGHTS OF GUNS.

No. 802,929.

Specification of Letters Patent.

Patented Oct. 24, 1905.

Application filed March 31, 1905. Serial No. 253,160.

To all whom it may concern:

Be it known that I, GEORGE FORBES, fellow of the Royal Society, a subject of the King of Great Britain, residing at 34 Great George 5 street, in the city of Westminster, England, have invented certain new and useful Improvements in Apparatus to be Used in Setting the Sights of Guns, of which the following is a specification.

At the present time when the distance of the target is known we have no accurate knowledge of the angle of elevation at which to set the gun. This depends not only on the distance, but also upon the resistance of the air, which varies with its density, and upon the muzzle velocity, which varies with the temperature of the cordite and the wear of the gun and the rate at which the gun and target are moving relatively to each other. The elevation, therefore, can only be ascertained by lengthy calculations, and consequently it is practically necessary to always fire one or more sighting-shots from a "ranging-gun." In order to overcome these difficulties, I modify the method of sighting guns, and I combine with a range-finder such as is described in the specification of my patent dated the 27th of May, 1902, No. 701,190, a device forming the subject of this invention, which may be called a "sight-setter" or "range-corrector," founded upon certain laws which I have discovered regarding the corrections to elevation caused by variations in muzzle velocity and air resistance.

Figure 1 is a sectional elevation showing in its most complete form the arrangement I adopt for a barbette-gun, the range-finder being seen in end elevation. Fig. 2 is a rear elevation, and Fig. 3 a plan, of the range-finder and its carriage to a larger scale. Fig. 4 is a sectional elevation, and Fig. 5 a plan, of the range-finder carriage. Fig. 6 is a horizontal section of the middle of the range-finder, and Fig. 7 is a transverse section. Figs. 4, 5, 6, and 7 are to a still larger scale. Fig. 8 is a sectional elevation, and Fig. 9 is a plan, to a larger scale than Fig. 1, of the sighting apparatus of the gun F, Fig. 1; and Fig. 10 is a sectional elevation of the left-hand end of it to a still larger scale. Fig. 11 is a side elevation of a modified arrangement. Fig. 12 is a sectional elevation, and Fig. 13 is a part plan of another modification.

The range-finder tube A is, say, forty feet long and is free to turn in roller-bearings B, carried by a frame consisting of four rods or

tubes B', braced together by rings B² and supported by a central sleeve B³. The range-finder has fixed at its ends a pair of Prandl prisms A', as in the range-finder described in my specification No. 701,190; but in order to obtain an erect image with astronomical eyepieces I substitute for the two Prandl prisms fixed at the middle of the tube a pair of prisms A², such as are described in the specification of my patent dated the 12th day of May, 1903, No. 727,776, having a pair of transmitting-faces and a pair of internally-reflecting faces, the faces of each pair being at right angles to each other and at an angle of forty-five degrees to the line of intersection of the other pair. The balloons also at the foci of the eyepieces A³ are fixed instead of movable, the image of the target being brought to the image of the balloons by turning a pair of thin prisms A⁴ between the prisms A' and A², as in my British specification No. 4,258 of 1903. The prisms A⁴ are fixed in a part tube A⁵ free to turn in the tube A. For this purpose the tube A⁵ has around its outside a cam-groove (not shown) with which a pin A⁶ on the nut A⁷ engages. The nut A⁷ is on a screw A⁸, and the cam-groove is so formed that at all ranges each turn of the screw moves the image of the target the same distance. A⁹ represents the object-glasses of the telescope, and A¹⁰ represents its eyepieces. The sleeve B³, carrying the range-finder, is mounted on a column C' on a carriage C, driven by a motor C² on rails C³ round the "top." The motor C² is a constant-speed electric motor driving the disk C⁴, resting on a friction-wheel C⁵, fixed to the spindle of a worm C⁶, gearing with a worm-wheel C⁷, on whose spindle is fixed a worm C⁸, gearing with a worm-wheel C⁹ on a shaft which also has fixed to it a toothed wheel C¹⁰, gearing with a toothed wheel C¹¹, gearing with a circular rack C¹². The motor C² is free to move in a circular guide C¹³ and has fixed to its under side a rack C¹⁴, gearing with a pinion on the wheel C¹⁵. By turning this wheel the motor is traversed in its guide, and the point of contact of the friction-wheel C⁵ with the disk C⁴ is moved toward and away from the center of the disk. In this way the speed of the train of gearing and of the carriage C can be varied and reversed. The range-finder is kept roughly directed on the target by the motor C² and is actuated by the observer in azimuth by means of the worm and worm-wheel B⁴, Fig. 4, and in elevation by turning it in the ball-bearings B. No claim

is made under the present application either to this form of range-finder or the method of supporting and directing it, and although this form is very convenient for the present purpose any other form may be employed in which there is a part moving in accordance with the distance of the object viewed.

The image of the balloons and the image of the target are made to coincide in spite of any change of range by the constant-speed electric motor D, driving the disk D', against which a friction-wheel A¹⁰ on the shaft of the screw A⁸ rests. The motor D can be moved to and fro in guides D² by a screw D', turned by the observer through bevel-gear by a wheel D⁴. By moving the motor D the position of the point of contact of the disk D' and wheel A¹⁰ is varied, so that the screw A⁸ can be driven in either direction at any desired speed. Connected to the end of the shaft of the screw A⁸ is a flexible shaft A¹¹, which is also connected to and drives the vertical shaft E, whose lower end carries a pin-wheel E', which drives, through an endless perforated steel band E², the pin-wheel E³, fixed to the vertical shaft E', passing through the roof of the turret in a line with the pivot about which the turret turns.

N² is a flexible shaft fixed to the end of the shaft E⁴ and communicating the motion to the sighting apparatus hereinafter described.

G G are two guide-plates rigidly fixed together and to one of the trunnions F of the cradle in which the gun recoils.

H is a slide which can be moved to and fro in guides between the plates G by a screw H' and handle H², worked by the sight-setter. The slide H is provided with bearings to receive trunnions fixed to a column J, on which the tube K of the telescopic sight is free to turn.

K' is the object-glass of the telescope. K² represents its eyepieces of different power, and K³ represents prisms to deflect the entering ray in the well-known manner.

The column J has rigidly fixed to it a tube J', having inside it a radius-bar L, on which it is free to slide.

L' is a link pivoted to the guide-bars G and to the radius-bar L, so that the latter is prevented from moving endwise.

The telescope-tube K carries a link K', connected to the tube J' by a set-screw J², by turning which the telescope-tube K is slightly turned upon the column J to correct for deflection.

The end of the radius-bar L carries a ball L², adjustable by a set-screw L³. The ball L² rests on a wedge M, and thus supports the telescope. The effect, therefore, of turning the screw H' is to vary the distance of the support from the trunnions of the telescope.

The wedge M is pivoted at M' to a slide N, which is moved to and fro between the guide-bars G by the screw N', driven by the flexible

shaft N² and resting upon the half-nut N⁴, fixed to the guide-plate G. This screw is pivoted at N⁴, and when desired it can be lifted out of the half-nut, and the slide and wedge can then be moved rapidly by hand for great changes of range. The rear end of the wedge M rests upon a horizontal row of balls O on a table forming part of the slide N. The under side of the wedge has fixed to it a lug M², which is embraced by a fork O', fixed to the vertical shaft O², which also has fixed to it a fork O³, embracing pins P', fixed to a sleeve P on the screw N'. The sleeve P is not screw-threaded, but it is slotted to receive a friction-wheel Q, working as a nut on a quick-threaded portion of the screw N'.

R is a disk resting on the friction-wheel Q, and R' is a worm-wheel fixed on its spindle and gearing with a worm R², fixed to the spindle of a worm-wheel R³, gearing with a worm R⁴, fixed to the spindle of a constant-speed electric motor R⁵.

When the screw N' is stationary, the motor R⁵ screws the wheel Q along it until it reaches its mid-position, as shown, whereupon it ceases to revolve. When the screw N' is turning, it causes the wheel Q to move laterally until it reaches such a distance from the center of the disk R that it is driven by the motor R⁵ and disk R at the same speed as the screw N', whereupon its lateral movement ceases. The wheel Q during its lateral movement carries the sleeve P with it, so turning the shaft O², which turns the wedge M about its pivot M'. There is a blank space at each end of the quick-threaded portion of the screw N', so that when the wheel Q comes near the edge of the disk the screw ceases to traverse it, so that it cannot be carried out of contact with the disk R by any change of range, however rapid. The edges of the disk R are dished so as to cause the wheel Q to always tend to reengage with the screw.

The rear end of the motor has fixed to it a rod R⁶, which is supported by a standard N⁵, fixed to the slide N, and is adjustably held by a set-screw N⁶. The motor has upon it a scale R⁷, and the slide N a pointer N⁷, by which the position of the motor relatively to the slide can be read. The sleeve P also carries a scale P², and the motor a pointer R⁸, so that the position of the sleeve relatively to the motor can be read. The slide N has fixed to it a pin N⁸, engaging with a cam-groove in a cylinder S, free to turn in bearings S', fixed to the guide-plate G. The cylinder has upon it a scale S², divided into hundreds of yards, short or over, and a nut H³ on the screw H' carries a pointer H⁴. The slide H on the screw H' also carries a pointer H⁵, which moves along the scale G' on the plate G, indicating muzzle velocities.

The central vertical section of the wedge M is a curve of which the abscissæ are proportional to the ranges, while the ordinates give

to the gun the corresponding elevation required for a stationary target at those ranges under normal conditions. Other vertical sections of the wedge through the pivot M' are 5 similar curves for targets approaching and receding at different rates. These curves can readily be drawn from the range-tables, which are usually prepared for each gun or class of gun. A simple way of constructing the wedge 10 is to cut out a number of these curves from thin sheet metal and fix them in proper order in vertical planes radiating from a point. The spaces between the sheets are then filled 15 up with plaster-of-paris or the like, and the surface of the plaster between the tops of the plates is smoothed off. The model of the wedge formed in this way is then reproduced in hard metal by any ordinary method, such as electrodeposition or casting.

20 *Method of Using the Apparatus.*

Before going into action two corrections—namely, those for muzzle velocity and density of the air—should be made.

25 *Muzzle velocity.*—As is well known, this depends on the weight of the charge, the temperature of the cordite of which it consists, and the amount of wear to which the gun has been subjected. When these factors have been 30 ascertained, the approximate muzzle velocity is determined by tables. The officer in charge of the gun turns the wheel H^2 until the pointer H^3 comes to the proper figure on the scale G' .

35 *Air density.*—This may readily be determined either (1) by thermometer, barometer, and hygrometer, or (2) by weighing a hollow sphere of thin glass, preferably mounted as part of a steelyard, or (3) neglecting moisture by the height of liquid in a vertical tube dipping into liquid in a bottle hermetically sealed at the neck. Different air densities have the same effect as change of range during flight, and therefore the necessary correction is made by turning the wedge M about its pivot 40 M' . This is done by the officer in charge of the gun by loosening the screw N^6 and moving the motor until the proper figure on the scale K' is opposite the pointer N' on the slide N . This has the effect of shifting the disk R 45 relatively to the wheel Q , or, in other words, altering the normal or mid position of the wedge. The motor when thus brought to its proper position is again clamped by the screw N^6 .

55 *Range-finder.*—It is the duty of the officer in charge of the range-finder to keep the target in the field of view and to so regulate the speed of the screw A^8 , by shifting the motor D by means of the handle D' , as before described, that the image of the balloons coincides with that of the target. If this be done, then since the screw N' is turned, as before described, at the same speed as the screw A^8 it follows that the wedge M is automatically moved to and fro longitudinally in such a

manner that it is always in its proper position corresponding to the range, whatever that may be. As explained above, also any change in the speed of revolution of the screw N' turns the wedge M more or less about its 70 pivot M' , and in this way the curve of the wedge corresponding to that rate of change of range is automatically brought beneath the ball L .

5. *Aiming.*—It follows from what has been said above that the officer in charge of the gun only has to use his judgment in allowing for the effect of the wind, and he corrects for this and for the known deflection at the different ranges by turning the screw J^2 . If 80 now the gun is elevated and trained so as to direct the telescopic sight onto the target, the projectile cannot fail to hit, provided the preliminary adjustments have been correctly made. If, however, the projectile falls short 85 of or passes over the target, which it will do if a mistake has been made in calculating the muzzle velocity, the officer in charge of the range-finder or another "shot-spotter" informs the officer in charge of the gun of the 90 amount of the error, whereupon he turns the wheel H^2 until he brings the pointer H^3 opposite the proper figure on the "short-and-over" scale S^2 , and thereby makes the required correction. As the amount of these corrections varies with the range, they are shown 95 by curved lines on the surface of a cylinder which is rotated by the longitudinal movement of the wedge.

The vertical shaft E' may have fixed to it 100 a second pin-wheel driving an endless perforated band running round the ship and conveying the movement of the range-finder to another gun or to several guns. In fact, all the guns in the ship may in this manner be 105 controlled simultaneously by a single range-finder. The motion of the band should be made so great—say six inches, to represent one hundred yards range—so as to avoid all trouble from stretching, temperature, and 110 backlash.

Fig. 11 shows a modified arrangement in which the sight-setter in place of being supported by the trunnion of the cradle is carried by the "false trunnion"—that is to say, 115 a trunnion parallel to the trunnion of the cradle and turning with it. In this figure the "dot-and-peck" lines show the parts already in use in connection with naval guns and the full lines show the range-setter. T 120 is the false trunnion, connected by the rod T' to a crank or eccentric on the trunnion of the cradle, so that it turns with the latter. In this arrangement the guide-plates G are fixed to the false trunnion and are vertical instead 125 of horizontal, as before, and the slide N and the parts connected to it are counterbalanced by the weight U . The telescope-tube K is horizontal instead of vertical. In other respects the arrangement is similar to that above 130

described; and the parts are marked with the same letters. Fig. 12 shows a somewhat different arrangement which, however, works in a similar manner, and Fig. 13 is a part plan of the same. In this case the telescope-tube K is pivoted at V' inside a tube V. The tube V is pivoted about a horizontal pin V², which is at an angle of about one and one-half degrees less than 70 a right angle to the bore of the gun to compensate for drift; the final corrections for differences of drift at different ranges and for side wind being made by turning the telescope about V' by means of a set-screw at its rear end, which is not shown. The pin V² is fixed to a block V³ free to move on guides fixed to the plate G to correct for muzzle velocity, as shown by the position on the scale G' of the pointer H', fixed to the tube V. The block and tube V are moved to and fro by a rack V⁴, fixed to the tube, which gears with a pinion W' on a spindle W², working in bearings carried by a sleeve W on the tube V. The wedge M is carried by the sleeve W, and 75 the sleeve is moved to and fro by the screw N', driven, as above described, by the range-finder. The screw N' is prevented from moving longitudinally by a link N², connected at one end to it by a universal joint N¹⁰ and having its other end pivoted to the bracket G², fixed to the plate G. The wedge and telescope rest on a ball X', carried by an arm X, free to move along a guide formed in the bracket G³, fixed to the plate G. The motor 80 R⁵ is also carried by the bracket G³ and can be moved to and fro along it to make the correction for air density by means of the screw and wheel Y. The spindle of the motor R⁵ carries a disk R, which runs in contact with 85 a friction-wheel Q, carried by the arm X and working as a nut on the quick-threaded screw Z, which has fixed to it a worm-wheel Z', gearing with the worm Z² on the flexible shaft Z³, which is driven by bevel-gear Z⁴ from the screw N'. In this manner the ball X', on 90 which the wedge is supported, is caused to traverse from side to side, according to the movement of the target, producing an exactly similar result to that obtained by the lateral 95 movement of the wedge beneath the ball L', as described in the first arrangement.

Although I have described the range-corrector as being fixed to the cradle of the gun, this is not essential. Identically the same instrument may be used when it is entirely independent of the gun for calculating the proper elevation. In this case all that is required is a circle or other means for reading the angle between the guide-bars G and the 100 column J, or the radial bar L may be replaced by a graduated vertical rod resting on the wedge and free to move up and down in stationary guides. The screw H' may also instead of being automatically driven by the 105 range-finder be driven by a motor regulated

by the officer in charge of the gun in accordance with the ranges and rates of change given to him by the range-finder, or all motors may be dispensed with and the instrument be worked by hand.

In some cases instead of correcting for change of range during the flight of the projectile by turning the wedge about its pivot M', I make this correction by tilting the wedge about its thinner end or edge. The correction for muzzle velocity may, as in Figs. 12 and 13, be made by moving the wedge laterally parallel to its edge, the parallel sections of the wedge being in this case the range curves of different muzzle velocities.

In place of a wedge I may employ a rotating cam-surface; but this is not usually desirable.

I wish it to be understood that the term "range-finder" used in the following claims is not intended to include a telescope or telescopic sight at a known height above the object aimed at and whose range of depression therefore indicates the distance of the object. By "variable-speed" motor I mean either a motor whose speed can be varied or a constant-speed motor provided with variable-speed gear. I also wish it to be understood that I am aware that cams or curves have before been proposed for determining the proper elevation of guns and that I make no broad claim to them; but

I declare that what I claim is—

1. The combination of a range-finder having in it a part which moves with changes of the distance of the object viewed a range-corrector, and means for operating the range-corrector from the moving part.

2. The combination of a range-finder having in it a part which moves with changes of the distance of the object viewed, and a variable-speed motor driving the moving part.

3. The combination of a range-corrector, and a variable-speed motor operating it.

4. The combination of a range-finder having in it a part which moves with changes of the distance of the object viewed, a variable-speed motor driving the moving part, a range-corrector, and means for operating the range-corrector from the moving part.

5. The combination of a range-corrector, consisting of a wedge having a curved surface, and means for moving the wedge longitudinally in a straight line.

6. The combination of a range-corrector, consisting of a wedge having a curved surface, and means for turning the wedge about an axis at right angles to its edge.

7. The combination of a range-corrector, consisting of a wedge having a curved surface, a sight supported by the wedge, a pivot about which the sight is free to turn and means for moving the wedge toward and away from the pivot.

8. The combination of a range-corrector,

consisting of a wedge having a curved surface, a sight, a pivot about which the sight is free to turn means for moving the wedge toward and away from the pivot, and an arm 5 fixed to the sight and supported by the wedge.

9. The combination of a range-corrector, consisting of a wedge having a curved surface, a sight supported by the wedge, a pivot 10 about which the sight is free to turn means for moving the wedge toward and away from the pivot, and means for varying the distance between the pivot and the point of support.

10. The combination of a range-corrector, consisting of a wedge having a curved surface, a sight, a pivot about which the sight is free to turn means for moving the wedge toward and away from the pivot, an arm fixed 20 to the sight and supported by the wedge, and means for varying the length of the arm.

11. The combination of a range-finder having in it a part which moves with changes of the distance of the object viewed, a range-corrector, consisting of a wedge having a 25 curved surface, and means for causing the moving part to move the wedge longitudinally in a straight line.

12. The combination of a range-finder 30 having in it a part which moves with changes of the distance of the object viewed, a range-corrector, consisting of a wedge having a curved surface, and means for causing the moving part to turn the wedge about an axis 35 at right angles to its edge.

13. The combination of a range-finder having in it a part which moves with changes of the distance of the object viewed, a range-corrector, consisting of a wedge having a 40 curved surface, a screw, carried by the wedge a nut engaging with the screw, and means for driving the screw from the moving part.

14. The combination of a range-finder having in it a part which moves with changes 45 of the distance of the object viewed, a range-corrector, consisting of a wedge having a curved surface, a screw, carried by the wedge a nut engaging with the screw, a second screw, a friction-wheel mounted as a nut on 50 it, means causing the movement of the nut on the screw to move one end of the wedge transversely, a disk in contact with the friction-wheel, a constant-speed motor driving the disk, and means for driving the two 55 screws from the moving part.

15. The combination of a range-finder having in it a part which moves with changes 60 of the distance of the object viewed, a range-corrector, consisting of a wedge having a curved surface, means for causing the moving part to move the wedge longitudinally in a straight line, and a variable-speed motor driving the moving part.

16. The combination of a range-finder 65 having in it a part which moves with changes

of the distance of the object viewed, a range-corrector, consisting of a wedge having a curved surface, means for causing the moving part to turn the wedge about an axis at right angles to its edge, and a variable-speed 70 motor driving the moving part.

17. The combination of a range-finder having in it a part which moves with changes of the distance of the object viewed, a range-corrector, consisting of a wedge having a 75 curved surface, a screw, carried by the wedge a nut engaging with the screw, means for driving the screw from the moving part, and a variable-speed motor driving the moving part. 80

18. The combination of a range-finder having in it a part which moves with changes of the distance of the object viewed, a range-corrector, consisting of a wedge having a curved surface, a screw, carried by the 85 wedge a nut engaging with the screw, a second screw, a friction-wheel mounted as a nut on it, means causing the movement of the nut on the screw to move one end of the wedge transversely, a disk in contact with the friction-wheel, a constant-speed motor driving the disk, means for driving the two screws from the moving part, and a variable-speed motor driving the moving part.

19. The combination of a gun, a guide parallel to the gun and turning with it, a block free to move in the guide, a sight carried by the block, a slide free to move in the guide, a screw carried by the slide, a nut gearing with the screw, a wedge carried by the slide, and 90 an arm connected to the block and resting on the wedge. 100

20. The combination of a gun, a guide parallel to the gun and turning with it, a block free to move in the guide, a sight carried by 105 the block, a slide free to move in the guide, a screw carried by the slide, a nut gearing with the screw, a wedge carried by the slide, a telescopic arm resting on the wedge and having one member fixed to the block, and a link 110 pivoted to the other member and to the guide.

21. The combination of a gun, a guide parallel to the gun and turning with it, a block free to move in the guide, a sight carried by 115 the block, a slide free to move in the guide, a screw carried by the slide, a nut gearing with the screw, a wedge pivoted to the slide, and an arm connected to the block and resting on the wedge. 120

22. The combination of a gun, a guide parallel to the gun and turning with it, a block free to move in the guide, a sight carried by the block, a slide free to move in the guide, a screw carried by the slide, a nut gearing with 125 the screw, a wedge pivoted to the slide, a telescopic arm resting on the wedge and having one member fixed to the block, and a link pivoted to the other member and to the guide. 130

23. The combination of a gun, a guide parallel to the gun and turning with it, a block free to move in the guide, a sight carried by the block, a slide free to move in the guide, a screw carried by the slide, a nut gearing with the screw, a wedge pivoted to the slide, an arm connected to the block and resting on the wedge, a friction-wheel mounted as a nut on the screw, means causing the movement of the nut on the screw to move one end of the wedge transversely, a disk in contact with the friction-wheel, and a constant-speed motor driving the disk.

24. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a telescopic arm resting on the wedge and having one member fixed to the block, a link pivoted to the other member and to the guide, a friction-wheel mounted as a nut on the screw, means causing the movement of the nut on the screw to move one end of the wedge transversely, a disk in contact with the friction-wheel, and a constant-speed motor driving the disk.

25. The combination of a gun, a guide parallel to the gun and turning with it, a block free to move in the guide, a sight carried by the block, a slide free to move in the guide, a screw carried by the slide, a nut gearing with the screw, a wedge carried by the slide, an arm connected to the block and resting on the wedge, a nut carried by the block, a screw gearing with this nut, a second nut on this screw, a pointer carried by it, a cylindrical scale free to turn about its axis, read by the pointer and having in it a cam-groove, and a pin on the slide engaging with the cam-groove.

26. The combination of a gun, a guide parallel to the gun and turning with it, a block free to move in the guide, a sight carried by the block, a slide free to move in the guide, a screw carried by the slide, a nut gearing with the screw, a wedge carried by the slide, a telescopic arm resting on the wedge and having one member fixed to the block, a link pivoted to the other member and to the guide, a nut carried by the block, a screw gearing with this nut, a second nut on this screw, a pointer carried by it, a cylindrical scale free to turn about its axis, read by the pointer and having in it a cam-groove, and a pin on the slide engaging with the cam-groove.

27. The combination of a gun, a guide parallel to the gun and turning with it, a block free to move in the guide, a sight carried by the block, a slide free to move in the guide, a screw carried by the slide, a nut gearing with the screw, a wedge pivoted to the slide, an arm connected to the block and resting on the wedge, a nut carried by the block, a screw

gearing with this nut, a second nut on this screw, a pointer carried by it, a cylindrical scale free to turn about its axis, read by the pointer and having in it a cam-groove, and a pin on the slide engaging with the cam-groove.

28. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a telescopic arm resting on the wedge and having one member fixed to the block, a link pivoted to the other member and to the guide, a nut carried by the block, a screw gearing with this nut, a second nut on this screw, a pointer carried by it, a cylindrical scale free to turn about its axis, read by the pointer and having in it a cam-groove, and a pin on the slide engaging with the cam-groove.

29. The combination of a gun, a guide parallel to the gun and turning with it, a block free to move in the guide, a sight carried by the block, a slide free to move in the guide, a screw carried by the slide, a nut gearing with the screw, a wedge pivoted to the slide, an arm connected to the block and resting on the wedge, a friction-wheel mounted as a nut on the screw, means causing the movement of the nut on the screw to move one end of the wedge transversely, a disk in contact with the friction-wheel, a constant-speed motor driving the disk, a nut carried by the block, a screw gearing with this nut, a second nut on this screw, a pointer carried by it, a cylindrical scale free to turn about its axis, read by the pointer and having in it a cam-groove, and a pin on the slide engaging with the cam-groove.

30. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a telescopic arm resting on the wedge, and having one member fixed to the block, a link pivoted to the other member and to the guide, a friction-wheel mounted as a nut on the screw, means causing the movement of the nut on the screw to move one end of the wedge transversely, a disk in contact with the friction-wheel, a constant-speed motor driving the disk, a nut carried by the block, a screw gearing with this nut, a second nut on this screw, a pointer carried by it, a cylindrical scale free to turn about its axis, read by the pointer and having in it a cam-groove, and a pin on the slide engaging with the cam-groove.

31. The combination of a gun, a guide parallel to the gun and turning with it, a block free to move in the guide, a sight carried by the block, a slide free to move in the guide, a screw carried by the slide, a nut gearing with

- the screw, a wedge carried by the slide, an arm connected to the block and resting on the wedge, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.
32. The combination of a gun, a guide parallel to the gun and turning with it, a block free to move in the guide, a sight carried by the block, a slide free to move in the guide, a screw carried by the slide, a nut gearing with the screw, a wedge carried by the slide, a telescopic arm resting on the wedge and having one member fixed to the block, a link pivoted to the other member and to the guide, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.
33. The combination of a gun, a guide parallel to the gun and turning with it, a block free to move in the guide, a sight carried by the block, a slide free to move in the guide, a screw carried by the slide, a nut gearing with the screw, a wedge pivoted to the slide, an arm connected to the block and resting on the wedge, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.
34. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a telescopic arm resting on the wedge and having one member fixed to the block, a link pivoted to the other member and to the guide, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.
35. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a friction-wheel mounted as a nut on the screw, means causing the movement of the nut on the screw to move one end of the wedge transversely, a disk in contact with the friction-wheel, a constant-speed motor driving the disk, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.
36. The combination of a gun, a guide parallel to the gun and turning with it, a block free to move in the guide, a sight carried by the block, a slide free to move in the guide, a screw carried by the slide, a nut gearing with the screw, a wedge pivoted to the slide, a telescopic arm resting on the wedge, and having one member fixed to the block, a link pivoted to the other member and to the guide, a friction-wheel mounted as a nut on the screw, means causing the movement of the nut on the screw to move one end of the wedge transversely, a disk in contact with the friction-wheel, a constant-speed motor driving the disk, a nut carried by the block, a screw gearing with this nut, a second nut on this screw, a pointer carried by it, a cylindrical scale free to turn about its axis, read by the pointer and having in it a cam-groove, a pin on the slide engaging with the cam-groove, a range-finder having in it a part which moves with changes of the distance of the object viewed, a variable-speed motor driving the moving part, and means operated by the moving part for turning the first-mentioned screw.

GEORGE FORBES.
